UNITED STATES PATENT OFFICE.

ENOS PATTEN AND THOMAS DAVEY, OF LYNN, MASSACHUSETTS; SAID DAVEY ASSIGNOR TO SAID PATTEN.

SOLE BUFFING, CLEANING, AND EDGE SETTING MACHINE.

SPECIFICATION forming part of Letters Patent No. 253,169, dated January 31, 1882.

Application filed June 6, 1881. (No model.)

To all whom it may concern:

Be it known that we, ENOS PATTEN, a citizen of the United States, and THOMAS DAVEY, a subject of the British Empire, both residing at 5 Lynn, in the county of Essex and Commonwealth of Massachusetts, have invented certain new and useful Improvements in a Combined Sole Buffing, Cleaning, and Edge Setting Machine; and we do hereby declare the following to be 10 a full, clear, and concise description of the invention, such as will enable others skilled in the art to which it pertains to make and use the same, reference being had to the accompanying drawings, which form part of this 15 specification.

Our invention relates to that class of machines used for the purpose of edge-setting, sole-buffing, and sole-cleaning in the manufacture of boots and shoes.

20 The object of the invention is to provide a simple and effective apparatus which shall be adapted to be used for all the purposes above specified by a simple interchange of certain parts.

25 The invention consists in certain details of construction, all hereinafter fully set forth and specifically claimed.

In the accompanying drawings, Figure 1 represents a front elevation of our improved 30 machine; Fig. 2, a side elevation; Fig. 3, a plan, partly in section. Fig. 4 shows a front elevation of an edge-setting tool adapted for use in connection with the machine in the place of the buffer. Fig. 5 is a plan view of the 35 same.

In Figs. 1 and 2 of these drawings, A represents a counter-shaft, suspended from the ceiling by suitable hinges, b b. It is intended to receive motion from a band on pulley a, and is 40 provided with another pulley, a', for transmitting the motion received. On the shaft A is suspended a frame, B, adapted to swing freely thereon. To this is pivoted a lower frame, C, by central pivot, c, through the end bars, 45 which pivot permits the lower frame to turn on the upper, thus inclining the plane of one frame to that of the other. In the lower frame is hung a shaft, D, provided with pulley f, connected to pulley a' by band h, and with a second pulley, e, to transmit motion received. On

the shaft D is pivoted a bow or frame, E, to which is fixed arm E' in line with pulley e. On the outer end of this arm is pivoted axially therewith a short extension, F, (shown in section in Fig. 3,) to which is attached by transverse pivot a head, G, the pivot passing through a hole in the tongue of the head G. In the head G revolves a shaft, H, carrying a pulley fixed thereto, and revolving in a recess in the head in line with pulley e. A band connects the two pulleys, and communicates motion to the shaft H. On one end of the shaft H is a buffer, M, usually covered with sand-paper, which revolves with the shaft. Outside of that, loose, but held on by a screw, is a 60 handle, N. Another handle, also loose, is shown at m on the other side of the head G. Outside this and on the end of H is a pad, L, of ordinary construction, slightly flexible and covered with sand-paper. Instead of this, a 65 brush may be attached. By taking hold of one or both of these handles the tool may be turned and applied to work in any direction. The tool may be turned vertically from the pad L by means of the axial point or pivot 70 between parts of arms E and F, or, using both handles, the tool may be turned horizontally to apply the buffer M.

The interchangeable tool for edge-setting is shown in Figs. 4 and 5. In this is a shaft, 4, 80 corresponding to shaft H in tool heretofore described. It is carried in a corresponding head formed with a tongue like the tongue i on G. The shaft turns in bearings 9 9. A block, 10, fixed to one side of the head, has 85 fixed thereto a handle, 3, and an arm-rest, 13, to enable the operator to steady the tool. The shaft 4 is bored out longitudinally, and a pin, 7, passes centrally through such shaft, and is held in position by a coil-spring, 14. The edge-setting tool is removed by pressing this pin 7 inward against the tool, the spring returning it to position when released. The outer end of pin 7 is provided with a knob or handle, as shown. A loop is pivoted within the head, 95 provided with an eye, 12, by which it may be suspended by flexible connections to the ceiling by a spring, such as that shown at 15 in Fig. 2. The tool is represented as in position, or as when suspended, in Fig. 4. The tongue 100

may be placed on the end of arm F in place of tongue *i* of head G, and the pulley on shaft 4 connected by band *p* to pulley *e* in the same manner as the pulley is represented as connected in Fig. 2. The same power is adapted to move either, and the frame and arm are adapted to receive either.

Having thus described our invention, what we claim is—

- 10 In combination, the suspended shaft A, provided with pulleys *a a'*, pivoted frames B and C, shaft D, carrying pulleys *e* and *f*, frame E,

arm E', arm F, axially pivoted thereto, and head G, carrying shaft, pulley, and tools, all as set forth.

In testimony whereof we have signed our names to this specification in the presence of two subscribing witnesses.

ENOS PATTEN.
THOMAS DAVEY.
